UNITED STATES PATENT OFFICE

125,279

DESIGN FOR AN UMBRELLA RIB TIP

Joseph Levin, Lancaster, Pa.

Application December 4, 1940, Serial No. 97,068

Term of patent 14 years

To all whom it may concern:

Be it known that I, Joseph Levin, a citizen of the United States of America, residing at Lancaster, in the county of Lancaster and State of Pennsylvania, have invented a new, original, and ornamental Design for an Umbrella Rib Tip, of which the following is a specification, reference being had to the accompanying drawing, forming a part thereof.

In the drawing:

I claim:

The ornamental design for an umbrella rib tip, as shown.

JOSEPH LEVIN.
